LEWIS W. CHUBB, OF EDGEWOOD PARK, PENNSYLVANIA, ASSIGNOR TO WESTINGHOUSE ELECTRIC AND MANUFACTURING COMPANY, A CORPORATION OF PENNSYLVANIA.

SHIELDING SYSTEM FOR VAPOR-CONVERTERS.

1,272,621.

Specification of Letters Patent.

Patented July 16, 1918.

Application filed August 9, 1915. Serial No. 44,417.

To all whom it may concern:

Be it known that I, LEWIS W. CHUBB, a citizen of the United States, and a resident of Edgewood Park, in the county of Allegheny and State of Pennsylvania, have invented a new and useful Improvement in Shielding Systems for Vapor-Converters, of which the following is a specification.

My invention relates to shielding systems for vapor converters, and it has for its object to provide means and apparatus whereby the arc, in devices of the character indicated, shall be restricted to certain well defined portions of the anode.

15 The single figure of the accompanying drawing is a side view, partially in elevation and partially in section, of a vapor converter embodying a preferred form of my invention.

20 In the operation of a vapor converter, current is conveyed, from an electrode which is temporarily positive to one which is temporarily negative, by a stream of electrons emitted from the latter and impinging upon the former.

25 The anodes employed in vapor converters are generally solid in nature, being formed of some refractory impervious material, such, for example, as steel. In the manufacture of the converter, it is customary to treat out the interior of the container in order to remove the occluded gases from the material thereof. It has been found substantially impossible to remove the occluded 35 gases from all portions of an anode of the character indicated, there being a strong tendency of the treating out arc to concentrate upon the more exposed portions, leaving the less exposed portions with a certain amount of occluded gases. By my invention, I provide means whereby, in the normal operation of a converter, said electron stream is controlled, and the power arc is therefore maintained upon portions of 40 the anodes which have been treated out, and the liberation of occluded gases is therefore reduced to a minimum.

45 Referring to the accompanying drawing for a more detailed understanding of my invention, I show the container of a vapor converter of the metal-case type at 1. Said container is provided with a pair of solid anodes 2 and 3 and with a cathode 4, preferably formed of vaporizable reconstructing material, such, for example, as mercury or

suitable amalgams. The anodes 2 and 3 are connected, respectively, to the terminals of an alternating-current source 5, and the cathode 4 is connected to the mid point of the source 5 through a load 6, as is usual in the rectifier art. The cathode 4 is maintained in an active position by any suitable means, such, for example, as a keep-alive circuit 7, and the interior of the container 1 is highly exhausted. Each of the anodes 2 and 3 may be provided with suppressor shields 8 and 9 of the type shown and claimed in a copending application of S. W. Farnsworth, Serial No. 44,429, filed Aug. 9, 1915, and assigned to the Westinghouse Electric & Manufacturing Company.

Briefly speaking, the suppressor shields 8 and 9 comprise cylindrical casings surrounding the anodes and provided with transverse diaphragms in the lower portions thereof, 75 said diaphragms supporting a plurality of conducting insulated tubular members 10-10. The tubular members 10-10 are connected to their associated anodes through resistance members 11-11 so that each tubular member reverses in polarity with its associated anode and thus tends to suppress reversal of the arc stream by the creation of space charges. I provide a cylindrical conducting member 12 within each of the shielding systems 8 and 9, and I connect the member 12 associated with each anode to the other anode, preferably including one of the resistance members 11 in the connection so as to eliminate the possibility of short circuits. The cylindrical members 12 preferably terminate somewhat above the active portions of the anodes 2 and 3.

Having thus described the structure of a vapor converter embodying my invention, 95 the operation is as follows: When the anode 2 is temporarily positive with respect to the cathode 4, a power arc passes therebetween, conveyed mainly by means of a stream of electrons emitted by the cathode and impinging upon the anode. The lower portion of the anode 2 is the only part thereof that can be effectively freed from occluded gases in the treating-out process and it is accordingly desirable that the power arc be restricted thereto. The anode 3 being charged negatively when the anode 2 is positive, a negative charge will be imparted to the shield 12 associated with the anode 2 and any electrons proceeding from the cathode 100 105 110

4 and tending to impinge upon the upper portion of the anode 2 will be repelled by the shield 12 associated therewith. The power arc will therefore be maintained within the desired limits.

5 In like manner, in a succeeding half cycle, the power arc proceeds to the anode 3, and the shield 12 thereof is negatively charged by reason of its connection to the anode 2, 10 resulting in the repulsion of all electrons tending to impinge upon untreated portions of the anode 3.

15 The impact of an electron with a molecule of residual gas in the arc path fractures said molecule and produces an additional electron and a residual positive ion of relatively large mass. There is a tendency for said positive ions to collect in the interior of a container and, if in sufficient number, their attraction to and bombardment 20 of an anode when temporarily negative may break down the negative electrode reluctance thereof and cause short circuiting of the device.

25 Said harmful phenomenon is largely prevented in my apparatus by the following actions. In the first place, positive ions generated outside the main shields are neutralized thereby before they can reach the anodes, in the manner set forth in the aforementioned Farnsworth application. Positive ions generated within a main shield, when the associated anode is positive in potential, are drawn to, and neutralized by, 30 the shield 12 and, when said anode is negative, said ions are repelled from the neighborhood thereof by the positive charge then existing on the shield 12.

40 I have, for simplicity, limited the above discussion to arc establishment and maintenance in the usual manner by means of a negative electron stream proceeding from the cathode to the anode, but, obviously, a similar shielding system could be applied 45 to a cathode to control the locus of impact of a positive ion stream proceeding from an anode to said cathode.

50 Throughout this description, I have explained the action of my device in accordance with the theory which seems most plausible in view of the present knowledge of the underlying phenomena. I desire it to be distinctly understood however that I do not confine myself to said theory of operation but merely present the same to aid 55 in an understanding of the invention.

60 While I have shown my invention in its preferred form, it will be obvious to those skilled in the art that it is susceptible of various minor changes and modifications without departing from the spirit thereof and I desire, therefore, that only such limitations shall be imposed thereupon as are imposed by the prior art or are specifically set forth 65 in the appended claims.

I claim as my invention:

1. In an evacuated electric device, the combination with a pair of electrodes, of means for initiating and maintaining an arc therebetween, and means operative through electrostatic action for restricting said arc to a portion only of one of said electrodes. 70

2. In an evacuated electric device, the combination with a pair of electrodes, one of which is solid and has occluded gases liberated from but a portion thereof, of means for initiating and maintaining an arc between said electrodes, and means operative through electrostatic action, for confining said arc to the gas-free portion of said solid 80 electrode.

3. In an evacuated electric device, the combination with a pair of electrodes, of means for initiating and maintaining an arc therebetween, and a conducting shield associated with a portion of one of said electrodes and electrostatically charged to prevent the flow of said arc to said portion of 85 said electrode.

4. In an evacuated electric device, the combination with a pair of electrodes, of means for initiating and maintaining an arc therebetween, and a conducting shield associated with a portion of one of said electrodes and charged to an opposite polarity 90 from an ionic stream flowing to said electrode to produce said arc, whereby said ions are substantially prevented from impinging upon said portion of said electrode.

5. In an evacuated electric device, the combination with a pair of electrodes, one of which is solid and has occluded gases liberated from but a portion thereof, of means for initiating and maintaining an arc between said electrodes, a conducting shield associated with the gas-bearing portion of said solid electrode, and means for charging said shield to a polarity opposite to that of said electrode when said arc tends to flow between said electrodes, whereby the ions 105 tending to produce said arc flow are substantially prevented from impinging upon said gas-bearing portions of said electrode.

6. In a vapor converter, the combination with a pair of anodes, of a cathode, a source of alternating current, a connection from one terminal of said source to one of said anodes and from the other terminal of said source to the remaining anode, a connection from said cathode to an intermediate point 110 in said source, a conducting shield associated with each of said anodes, and a conductive connection including a current-limiting device between each shield and the other anode, whereby the impingement of negative electrons from said cathode upon said anodes is controlled. 115

7. In a vapor converter, the combination with a pair of anodes and a cathode, of means for causing said anodes to alternate in 120 125 130

potential from a point above to a point below the potential of said cathode and for causing current to flow from either of said anodes to said cathode when said anode is positive with respect to said cathode, and a conducting shield associated with each anode and conductively connected to the other anode through a current-limiting device, whereby the flow of negative electrons from the cathode to each anode is subject to control.

8. In a vapor converter, the combination with a pair of anodes and a cathode, each of said anodes comprising gas-free and gas-bearing portions, of means for causing said anodes to alternate in potential from a point above to a point below the potential of said cathode and for causing current to flow from either of said anodes to said cathode when said anode is positive with respect to said cathode, and a conducting shield associated with the gas-bearing portions of each anode and conductively connected to the other anode through current-limiting means, whereby the travel of negative electrons, and consequently, of the arc, to said gas-bearing portions is prevented.

9. In a vapor converter, the combination with a pair of anodes alternating in potential, of a cathode, perforated suppressor shields associated with each of said anodes and electrically connected thereto through current-limiting devices, an auxiliary conducting shield associated with each anode, and connections from each auxiliary shield to the other anode, whereby the movement of electrons to each anode is controlled. 30 35

10. In a vapor converter, the combination with a pair of anodes alternating in potential, each of said anodes having gas-free and gas-bearing portions, of a cathode, perforated suppressor shields associated with each of said anodes and electrically connected thereto through current-limiting devices, an auxiliary conducting shield associated with each anode, and connections from each auxiliary shield to the other anode, whereby the movement of electrons to said gas-bearing portions and the consequent liberation of gas therefrom is substantially prevented. 40 45 50

In testimony whereof, I have hereunto subscribed my name this 31st day of July, 1915.

LEWIS W. CHUBB.
